William F. Ritchard

UNITED STATES PATENT OFFICE.

FRANK RAMPP, OF NEW YORK, N. Y., ASSIGNOR TO NATIONAL CARBON COMPANY, INC.,
OF NEW YORK, N. Y., A CORPORATION OF NEW YORK.

PORABLE ELECTRIC LIGHT.

1,350,887.

Specification of Letters Patent. Patented Aug. 24, 1920.

Application filed January 25, 1918. Serial No. 218,632.

To all whom it may concern:

Be it known that I, FRANK RAMPP, a citizen of the United States, residing in the borough of Bronx, county of Bronx, and 5 State of New York, have invented certain new and useful Improvements in Portable Electric Lights, of which the following is a specification, reference being had therein to the accompanying drawings, forming 10 part thereof.

My invention relates to self-contained or battery-operated portable electric lights, and relates more particularly to such a light adapted to be conveniently carried about 15 upon the person and provided with means such as a clip or hook for releasably connecting the light with some part of the apparel, such a hook-forming clip being combined with means for controlling the circuit 20 of the battery through the lamp. Objects of my invention are to provide a light of the kind mentioned which is simple in construction, inexpensive of manufacture, durable, dependable, and which is particularly 25 adapted to meet the requirements of soldiers as well as also conveniently usable by everyone. Other more particular objects and advantages of my invention will hereinafter appear.

30 My invention includes a novel arrangement or combination of circuit-controlling means and means for supporting the light, and includes more particularly a novel arrangement or combination of a circuit-controlling slide and a hook-forming clip carried thereby for releasably connecting the light with a part of the apparel of the person carrying the light, such hook or clip being more particularly adapted for engaging the belt of a soldier or other person, but also being adapted to support the light in other ways, as will hereinafter appear. My invention further includes features of 40 construction and combinations of parts, as will appear from the following description.

I shall now describe the portable electric light illustrated in the accompanying drawings embodying my invention and shall thereafter point out my invention in claims:

50 Figure 1 is an elevation of a portable electric light embodying my invention, shown in the position in which it is adapted to be carried, with the circuit in the open condition.

Fig. 2 is a side elevation of the same as 55 viewed from the left in Fig. 1.

Fig. 3 is a central longitudinal section, with parts in elevation, on a vertical plane indicated by the line 3—3 of Fig. 1 as viewed from the left.

60 Fig. 4 is a similar view with the circuit in the closed condition.

Fig. 5 is an end view as seen from below in Fig. 1.

Fig. 6 is a partial central longitudinal 65 section of the casing on a vertical plane indicated by the line 6—6 of Fig. 3 as viewed from the left.

Fig. 7 is a side or edge elevation of the circuit-controlling slide and the hook-forming 70 spring clip carried thereby and shown as formed in one piece therewith.

Fig. 8 is a partial transverse section on a horizontal plane indicated by the line 8—8 of Figs. 1 and 3 as viewed from below 75 in Fig. 1.

The most distinctive feature of my present invention is a resilient clip or supporting hook 1 which is combined with and projects from the rear end of an elongated circuit-controlling slide 2 alongside thereof and in overlapping relation thereto. The hook-forming spring clip 1 at its upper or rear end is shown as forming a continuation of the circuit-controlling slide 2, and is 80 shown as spaced therefrom and as joined thereto by a circulatory curved intermediate connecting part 3. The slide 2 is of greater length than the spring clip 1 so that the slide 2 projects forwardly or downwardly beyond the clip 1. From the curved intermediate spacing part 3 the clip 1 is shown as straight and as extending at an inclination downward and inward, and at its lower free end the clip 1 is disposed in 85 proximity to and is shown as normally in contact with the adjacent outer surface of the elongated slide 2, and this free end of the clip 1 is provided with a circularly rounded head or terminal part 4, as clearly 90 appears in the drawings. The spring clip 1 and the circuit-controlling slide 2 in the construction shown in the drawings are 95 formed of a single bent strip of suitable spring metal such as brass. In the construction illustrated in the drawings, the circuit-controlling slide 2 is shown as arranged longitudinally of a metallic casing tube 5

100

105

5

which forms the main part of a battery-containing and lamp-carrying casing, and the slide 2 is secured to and mounted upon the tubular casing part 5 by means of a 5 pair of eyelets or tubular rivets 6 which pass through end parts of the slide 2 and also through longitudinal slots 7 in the tubular casing part 5, whereby the slide 2 may have longitudinal sliding circuit-controlling 10 movement upon the tubular casing part 5, as will hereinafter appear. The elongated slide 2 is of slightly curved cross section, as most clearly appears in Fig. 8 of the drawings, for thereby conforming to the curvature of and closely fitting against the outer cylindrically curved surface of the casing tube 5.

At its lower or forward end the circuit-controlling slide 2 is provided with an outwardly indented end part 8 forming a short inner longitudinal groove or recess and a corresponding rounded outer projection at the end of the slide 2, as clearly appears in the drawings. An outwardly rounded 25 spring-pressed push button 9 projects from the inner to the outer side of the metallic tubular casing part 5 through a round hole 10 therein, and projects just below and just at the forward outwardly indented end 8 of 30 the slide 2, so that the push button 9 may be directly manually operated by pressures thereupon, and also so that when the slide 2 is pushed forward its outwardly indented end 8 will engage with the outwardly projecting rounded push button 9 and will, as 35 will be readily understood, exert a cam action upon and will override the push button 9, and will force this push button inward from its projecting open-circuit position appearing in Figs. 1, 2 and 3, to the depressed 40 circuit-closing position thereof appearing in Fig. 4. The rounded outwardly projecting push button 9 is carried by a spring metal strip 11 near the forward end thereof and 45 which at its rear end is firmly secured to the inside of the casing tube 5 by means of a tubular rivet or eyelet 12. In its middle part, this spring 11 is provided with a longitudinal slot 13 for the reception of the outer 50 or lower of the tubular rivets or eyelets 6 carried by the slide 2, and the spring 11 has an inwardly offset contact-making free end 14 which projects forwardly beyond the push button 9, as appears in the drawings. This 55 spring 11 together with the push button 9 carried thereby forms an automatically returning circuit-controlling member. As a matter of manufacturing convenience in riveting in place the upper slide-securing 60 eyelet 6, the adjacent outwardly spaced straight part of the sheet metal strip which forms the resilient clip 1 is shown as provided with an opening 15 for the insertion through this hole 15 of a suitable tool into

engagement with the upper slide-securing 65 eyelet 6.

The remaining parts of the portable electric light illustrated in the drawings as embodying my invention are substantially of a usual construction as heretofore made without my present invention, and will now be described sufficiently for the clear and complete understanding of my present invention. In its inner circuit-closing position, appearing in Fig. 4 of the drawings, the inwardly 70 offset end 14 of the contact spring 11 is in engagement or circuit-closing contact with the periphery or outer edge of a metallic circuit-completing contact disk 16 which is held in place upon and supported by a 75 metallic reflector 17 by means of an inwardly and outwardly flanged metallic screw-threaded lamp socket 18, the contact disk 16 and lamp socket 18, however, being electrically insulated from the metallic reflector 80 17 by means of interposed insulation, shown as an insulating disk 19 and an insulating ring or washer 20. This above described construction for electrically insulating the metallic contact disk 16 and metallic lamp 85 socket 18 from the metallic reflector 17 is disclosed in and forms the subject of the patent to Conrad Hubert, No. 1,157,395, of October 19, 1915, for portable electric light.

At its outer end the metallic reflector 17 is 90 shown as provided with a slight outturned flange which rests upon a corresponding slight inturned flange formed on the adjacent end of the metallic casing tube 5, the metallic reflector 17 thereby being in electrical connection with the casing tube 5. The reflector 17 is held in place upon the casing tube 5 by means of an end glass, shown as a usual lens 21, and this lens 21 is held in place by means of a usual end ring 105 22 screwed over the outer end of the casing tube 5, as clearly appears in the drawings. The inner end, which in the position of the light appearing in the drawings is the upper end, of the metallic casing tube 5 is closed 110 by means of a usual end cap 23 screwed thereon, and within this end cap 23 and carried thereby is a usual battery-engaging and circuit-completing tapered coiled thrust spring 24. The free inner end of the spring 115 24 engages the cup or zinc terminal 25 of a usual dry battery having an outer paper insulating tube 26, and the central carbon terminal 27 of the battery is in contact or in engagement with the central terminal 28 of a 120 usual miniature incandescent lamp, the usual terminal-forming base 29 of which is screwed into the lamp socket 18 and the bulb 30 of which is outwardly exposed within the reflector 17, as clearly appears in the drawings. While in the construction illustrated in the drawings, my invention is shown as embodied in a portable electric light of a 125

usual tubular form or type and shown as having a substantially usual metallic casing tube 5, it is to be clearly understood that my invention is in no sense restricted to either the tubular type of portable electric light or to a light having a metallic casing, and this fact will be readily understood by those versed in the art.

Referring now more particularly to the construction illustrated in the drawings, it will be noted that with the clip-carrying circuit-controlling slide 2 in the retracted position appearing in Figs. 1, 2 and 3, the outwardly indented button-operating end 8 thereof projects outwardly to a slightly greater extent than does the push button 9, and thereby serves to guard this push button against accidental inward circuit-closing movement which otherwise might possibly take place by reason of pressure upon the push button of some exterior object, such as a part of the apparel of the person carrying the light, and in this connection it is further to be noted that the slightly enlarged screw-threaded end of the casing tube 5 and the lens-holding end ring 22 provide also substantial assistance in preventing any such accidental pushing in of the push button 9, as will be readily understood. However, the push button 9 may be readily manually depressed for closing the circuit for short periods of lighting, and more conveniently for longer periods of lighting the slide 2 may be moved longitudinally from its open-circuit position, appearing in Figs. 1, 2, 3 and 6, to the circuit-closing position thereof illustrated in Fig. 4. In thus operating the clip-carrying circuit-controlling slide 2 it has been found that sliding movement, either for effecting the closed circuit or the open circuit condition, may be most conveniently effected by pressing with the thumb against the outwardly rounded projecting free end part 4 of the resilient clip 1.

The portable electric light embodying my invention may be most conveniently carried about by engaging the hook-forming spring clip 1 over the edge of a part of the apparel of the person carrying the light, so that such part of apparel will be received between the resilient clip 1 and the longitudinally extended circuit-controlling slide 2 alongside thereof and upon which the clip 1 is overlapped, and whereby the light will then be supported by the spring clip 1 and circuit-controlling slide 2, the curved part 3 forming a shoulder which will engage with or rest upon the upper free edge of the part 60 of the apparel upon which the light is supported. The spring clip 1 is particularly adapted for thus engaging the usual belt which is commonly worn, and particularly the usual service belt of a soldier, although

the light is equally well adapted for use by others. When the spring clip 1 is thus engaged with the belt, this spring clip passes to the inner side of the belt, while the body of the light including the casing part 5 hangs at the outside ready to be conveniently grasped for instant use. It is obvious of course that the spring clip 1 may also engage some other part of the apparel, for example, over the edge of a pocket, either at the inside or at the outside thereof. It is to be noted that the rounded lower or outer end 4 of the spring clip 1 besides serving as a convenient means for moving the circuit-controlling slide 2, as hereinbefore noted, also serves to permit the easy engagement of the lower end of the spring clip 1 in passing over the upper edge of the belt or pocket or other part of the apparel. In this connection it is to be noted as of importance that when the light is thus supported upon the apparel its weight is suspended from the circuit-controlling slide 2, and this weight will strongly tend to hold this slide at the open-circuit position, thereby effectively preventing its accidental movement to the closed-circuit position, as will be readily understood. As a matter of fact, after the light has been used and while the circuit is still closed, the light may be instantly returned to its position of engagement with the belt or other part of the apparel without first taking the trouble to move the slide to its open-circuit position, the downward pull upon the casing part 5 in effecting engagement of the clip 1, and particularly when the upper edge of the apparel part comes into contact with the shoulder-forming part 3, will cause the movement of the circuit-controlling slide 2 from the lower closed-circuit position thereof appearing in Fig. 4 to the upper open-circuit position thereof appearing in Figs. 1, 2, 3 and 6. In this operation the body of the light including the casing tube 5 moves downward, while the clip-carrying circuit-controlling slide 2 is held stationary by reason of its engagement with the apparel, as will be readily understood. Also, as a further advantage, it may be noted that the light may be conveniently hung up on a nail or other projection by means of the loop formed by the curved upper part 3 between the clip 1 and slide 2, and may be thus suspended either in an unlighted or in a lighted condition, it being noted in this connection that in this position the weight of the device is insufficient to overcome the friction of the slide 2, more particularly the friction of its lower end 8 with the spring-pressed push button 9. Besides the several advantages of use and operation above noted, it is to be further noted that the making of the supporting clip 1 and the slide 2 from a single continuous

41 strip of sheet metal greatly reduces the expense of manufacture, in addition to providing a superior construction as above noted.

5 It is obvious that various modifications may be made in the construction shown in the drawings and above particularly described within the principle and scope of my invention.

26 I claim:

1. A portable electric light comprising a battery-containing and lamp-carrying casing, and means for controlling the circuit of the battery through the lamp including a 15 circuit-controlling slide mounted on the casing for sliding circuit-controlling movement and provided with a clip forming a hook projecting alongside of the slide and adapted to receive between itself and the 20 slide a part of the apparel of the person carrying the light for thereby supporting the light, and in which the hook-forming clip is of less length than the slide and has a free rounded end disposed in proximity to 25 the slide and beyond which the slide projects.

2. A portable electric light comprising a battery-containing and lamp-carrying casing, and means for controlling the circuit of the battery through the lamp including a 30 circuit-controlling slide mounted on the casing for sliding circuit-controlling movement and provided with a clip forming a hook projecting alongside of the slide and toward the direction in which the slide moves to 35 close the circuit and adapted to receive between itself and the slide a part of the apparel of the person carrying the light, and in which the hook-forming clip is of less length than the slide and has a free rounded 40 end disposed in proximity to the slide and beyond which the slide projects.

3. A portable electric light comprising an elongated casing adapted to carry a lamp at one end thereof and to contain a battery for 45 the lamp, means for controlling the circuit of the battery through the lamp including a circuit-controlling slide mounted on the casing for sliding circuit-controlling movement longitudinally of the casing and arranged 50 to move toward the lamp-carrying end of the casing for closing the circuit, and a clip carried by the slide and forming a hook projecting therefrom alongside of the slide and projecting toward the lamp-carrying end of 55 the casing, such hook being adapted to releasably engage between itself and the slide a part of the apparel for thereby supporting the light and maintaining the slide at the open-circuit position and also whereby the 60 engagement of the light with the apparel will tend to move the slide from the closed-circuit position to the open-circuit position, and in which the hook-forming clip is of less length than the slide and has a free

rounded end disposed in proximity to the slide and beyond which the slide projects.

4. The invention claimed in claim 1 in which a spring-pressed circuit-controlling push button is disposed in the path of the projecting end of the slide so as to be operated thereby and also adapted to be independently manually operated.

5. A portable electric light comprising a battery-containing and lamp-carrying casing, and means for controlling the circuit of 75 the battery through the lamp including a circuit-controlling slide mounted on the casing for sliding circuit-controlling movement and provided with a clip forming a hook projecting alongside of the slide and 80 adapted to receive between itself and the slide a part of the apparel of the person carrying the light for thereby supporting the light, and in which the circuit-controlling means includes a manually operable 85 push button which is also adapted and arranged to be operated by the slide.

6. A portable electric light comprising an elongated battery-containing and lamp-carrying casing, a circuit-controlling slide 90 mounted on the casing for sliding circuit-controlling movement longitudinally thereof, an automatically returning circuit-controlling member adapted to be manually operated in its circuit-controlling movement 95 independently of the sliding circuit-controlling movement of the slide, and means carried by the slide for supporting the light.

7. A combined circuit-controlling and supporting device for a portable electric light, 100 such device comprising a single strip of bent material forming a circuit-controlling slide and a supporting hook overlapped upon the slide.

8. The invention claimed in claim 7 in 105 which the slide projects beyond the free end of the hook.

9. The invention claimed in claim 8 in combination with a circuit-controlling push button with which the projecting end of the 110 slide cooperates.

10. The invention claimed in claim 9 in which the projecting end of the slide is provided with a recess for receiving the outer 115 end of the push button.

11. A combined circuit-controlling and supporting device for a portable electric light, such device comprising a circuit-controlling slide and a resilient supporting hook carried by and extending alongside of 120 the slide, in combination with an automatically returning circuit-controlling member adapted to be operated by the slide and also adapted to be independently manually operated.

In testimony whereof I have affixed my signature to this specification.

FRANK RAMPP.
